UNITED STATES PATENT OFFICE.

WILLIAM C. ANDERSON, OF TOLEDO, OHIO, ASSIGNOR TO THE AMERICAN CUT GLASS COMPANY, OF CHICAGO, ILLINOIS.

DESIGN FOR A GLASS DISH.

SPECIFICATION forming part of Design No. 27,061, dated May 18, 1897.

Application filed March 20, 1897. Serial No. 628,545. Term of patent 7 years.

To all whom it may concern:

Be it known that I, WILLIAM C. ANDERSON, of Toledo, county of Lucas, and State of Ohio, have invented a certain new and original Design for a Glass Dish; and I do hereby declare that the following is a full, clear, and exact description of the invention, which will enable others skilled in the art to which it appertains to make and use the same, reference being had to the accompanying drawings, and to the figures of reference marked thereon, which form part of this specification.

This design relates to a glass dish, and particularly to the ornamentation of the exterior surface thereof.

The drawings represent, in Figure 1, a bottom plan view of a dish containing the design, and in Fig. 2 a section on lines *x-x*, Fig. 1.

The design is applicable to dishes, plates, and bowls.

The leading features of my design are a bottom portion consisting of a central stud with a many-pointed star for border and surrounded by an octagon, each point of the star having a checkering, and extending upon the side of the dish are two circular concentric rings, the ring of the smallest diameter encircling the star, with the ring of greater diameter encircling a row of irregularly-formed prismatic fields, with the outer border from the ring of greatest diameter extending to the top of the dish in irregular projection of conoidal form, with double-convex lines which meet at the apex of each conoid and centrally border the octagon of the center of the dish, with prismatic checkerings in the field of each conoid.

In the flattened portion of the bottom is a

central stud 1, bordered by a many-pointed star 2, with the star surrounded by an octagon 3, each point of the star having a checkering 4, consisting of minute prisms. Surrounding the star is a circular ring 5, cut into the body of the glass, the sides of which are inclined in pyramidal form from the peripheral surface to the bottom of the cut, with a like formed circular ring 6 concentric to the circular ring 5. Arranged between the concentric rings is a circular row of irregularly-shaped fields 7, the apex of each alternate field extending toward the top of the dish and the apex of the intermediate fields extending toward the base, each field being formed with a central prism and a checkering of lines forming triangular prisms.

The border of the dish consists of conoidal projections 8, and extending transversely of the dish are double-convex lines 9, which meet at 10 at the apex 11 of each concoid, with a checkering 12 upon each side of the lines 9. The lines 9 form an encircling border for the octagon. The circular lines and prismatic fields, together with the transverse double-convex lines and checkering of the conoidal projections, give to the dish a pleasing symmetry and highly-ornamental appearance.

What I claim is—

The design for a glass dish substantially as shown and described.

In testimony that I claim the foregoing as my own I hereby affix my signature in presence of two witnesses.

WILLIAM C. ANDERSON.
